UNITED STATES PATENT OFFICE

2,616,957

HIGH-VISIBILITY TRAFFIC SIGNAL

John Charles Thiem, Sr., Newport, Ky.

Application July 24, 1951, Serial No. 238,236

6 Claims. (Cl. 177—329)

1

This invention relates to a traffic signal and more particularly to a signal carrying a message which must be readily visible and legible even though the direct rays of the sun may at certain hours of the day impinge directly upon it. The invention is particularly adapted to traffic signals wherein a message is presented and where it is desired that that message be legible only during certain hours of the day. Thus for example many situations are found where a street is a one-way street in one direction during the morning hours and a one-way street in the opposite direction during the evening hours. It may be desirable to have a signal with the message "Do not enter" placed at each end of the street and to arrange the signal to be legible during the hours when traffic is approaching from the opposite direction.

It will be understood that while the invention is described herein particularly with reference to a traffic signal that it is equally adaptable for an advertising sign or the like.

Where a traffic signal or advertising sign is so placed that the direct rays of the sun may impinge upon it during the early morning or late afternoon hours the message is not readily legible at such times. It is an object therefore of the present invention to provide such a signal or sign which will be clearly legible even though substantially horizontal rays of sunlight impinge directly upon it.

It is an additional object of the invention to provide such a device that when the sign or signal is not illuminated the message cannot possibly be read, even when rays of light from the sun impinge upon it almost horizontally.

Further objects of the invention include the provision of a sign or signal as outlined above which will be simple and inexpensive in construction and which can be readily serviced when required.

These and other objects of the invention which will be pointed out in more detail hereinafter or which will be apparent to one skilled in the art upon reading these specifications I accomplish by that certain construction and arrangement of parts of which I shall now describe an exemplary embodiment.

Reference is made to the drawings forming a part hereof and in which:

Figure 1 is a front elevational view of a device according to the invention.

Figure 2 is a cross sectional view on an enlarged scale taken on the line 2—2 of Figure 1.

Figure 3 is an enlarged fragmentary cross sec-

2

tional view similar to Figure 2 showing details of the message panel and reflector fastening device.

Figure 4 is a fragmentary cross sectional view taken on the line 4—4 of Figure 2.

Figure 5 is a fragmentary detailed cross sectional view on an enlarged scale through the louver structure.

Figure 6 is a perspective view of a typical message panel.

Briefly, in the practice of my invention I provide a housing containing a light source. The light source is preferably a neon tube or other fluorescent light source and the housing may contain the necessary transformer for the light source as well as a flasher device or the like. The reflector will preferably be semi-cylindrical and will be of a highly reflective nature.

In front of the light source I place the message panel which will be of glass, plastic or similar material and which will be opaque and black in color except for the message which will be translucent.

In front of the message panel I provide a grill or louver member comprising a plurality of parallel slat members which are disposed at a slight inclination to the horizontal. A hood member extends forwardly from the message panel and past the slat structure to prevent stray side light and top light from impinging upon the message panel. The inside of the hood member, as well as all exposed parts of the grill member, are painted flat black to prevent light reflection. In the event that there is danger that the message may be read when the sign or signal is not illuminated, I place in front of the message panel and behind the grill structure a piece of fine mesh screen similar to window screen which is painted white. With this member in place and with the illuminating element not energized it is impossible to read the clear message in the black message panel.

Turning now to the figures for a more detailed description of the device I have illustrated a housing which may be of sheet metal or the like at 10. The housing proper may be assembled in any desired manner, as by welding, soldering, sheet metal screws or the like. At the back of the housing I prefer to provide the angle frame members 11 which serve for the fastening on of the back panel 12 which is shown as being secured to the housing 10 by the sheet metal screws 13. By removing the back panel 12 access may be had to the transformer indicated at 14 and flasher device indicated at 15. Transverse angle mem-

bers 16 are provided for further bracing the structure and hanger eyes 17 may be secured thereto in conventional manner so that the sign may be suspended from an overhead support.

The upper portion of the housing 10 extends well forwardly and may have its front edge slightly depressed as at 18, and it may be provided with the inturned flange 19 for strengthening purposes. At the bottom the housing preferably terminates at a point indicated at 20, but the side walls thereof are continued forwardly in a generally triangular configuration as indicated at 21. The lower edges of the portions 21 may be return bent as at 22 to give greater strength and rigidity.

A light source which may be a neon tube is indicated at 23 and it is supported by conventional hanger elements generally indicated at 24.

Angle pieces 25 are secured to the housing 10 at the top and bottom to serve as mounting elements for the message panel and the reflector. The reflector indicated at 26 is a generally semi-cylindrical piece of sheet metal having the flanges 27 at the top and bottom thereof. Holes 28 are provided in the flanges for the passage of the fastening screw indicated at 29. The numeral 30 indicates a rubber or other resilient gasket-like member, and the message panel is indicated at 31. At the top and bottom of the message panel strips or spacers 32 of the same thickness as the message panel are provided, and these have the holes 33 for the passage of the fastening screw 29. A frame element of generally U-shape is indicated at 34 which embraces the edges of the message panel 31 and the spacer members 32. The fastening screw 29 passes through holes in the frame members 34, through the hole 33 in the spacers 32, through holes in the gasket 30, through the holes 28 in the flanges of the reflector 26 and engage threadedly with the flanges 25 as best seen in Figure 3. The spacers 32 prevent breakage of the message panel if too much pressure is used on the fastening screws 29.

The reflector 26 will have its concave surface 43 reflectively treated. This may involve a white paint or the like with glass beads such as are used on motion picture screens.

The message panel itself is black and has at least an outer opaque surface. The message itself, as indicated at 35, will be translucent. The glass, if desired, may have a ground glass or granulated surface.

Indicated generally at 36 is a grill or louver structure which may be made from a single piece of sheet material. A series of slats 37 are cut and bent inwardly from the plane of the material to form a series of parallel slats, as best seen in Figure 2. The grill or louver structure 36, as well as all inside surfaces of the hood, will be given a flat black treatment to minimize reflectivity within the hood and on the structure 36.

While the extending hood and its downwardly turned front edge 18 will prevent direct sunlight from impinging upon the message panel 40, except when the sun is very low on the horizon, the structure 36 provides additional protection where the rays of the sun are practically horizontal. Thus I tilt the slats slightly with respect to the horizontal and this may of course be accomplished by having the slats at an angle other than a right angle with respect to the plane of the material from which they are struck out or preferably as shown in Figure 2 by mounting

the member 36 at a slight angle to the vertical. The angle is not too critical except that it should render the message clearly visible at a distance of approximately one block and the message should also be visible from a relatively short distance. I have determined that the angle of the slats with respect to the horizontal should be between about 2° and about 5°. The structure 36 is mounted in the hood, as best seen in Figure 4. Angle members 41 are secured by spot welding or the like to the opposed lateral edges of the structure 36. The angle members 41 are provided with holes for the passage of pins 42. The pins 42 are secured to spring strips 43 which are spot welded or otherwise secured to the plates 44 which in turn are welded to the side walls 21 of the hood. A hole 45 is provided in each of the plates 44 for entry of the pin 42. The louver structure is placed in position by withdrawing the spring member 43 by hand and passing the pin 42 through a suitable hole in the angle 41 and releasing the spring 43 whereupon the pin 42 will enter the hole 45. The structure 36 is thus pivotally hung in the side walls of the hood.

A similar structure is provided at the bottom on each side of the hood and on each side of the grill member 36 so that when it is desired to have access to the message plate the grill member may be freed from its mounting at the bottom and swung out counter-clockwise pivoting about the upper pin 42.

At 59 I have indicated a screen member which is mounted in a suitable frame element 51 which in turn is secured to the housing 10 in any desired manner as for example the bracket indicated at 52, and the screen 50 is painted white. With the screen 50 in place if at certain hours of the day the message panel is not to be illuminated, it will be impossible to read the message on the message panel even though rays of light from the sun impinge upon it substantially horizontally from the right, as seen in Figure 2. The rays of light falling upon the screen will give the appearance of a brilliant white panel and will completely obscure the clear message on the black panel behind it. If the tube 23 is energized, the message will clearly appear through the white painted screen. This situation will be found to be quite rare and for most purposes the device will be completely operated without the member 50 in position. The slats 37 placed at an angle, as pointed out above, will prevent in most cases the impingement of light directly upon the message panel.

From the foregoing description it will be understood that the invention is not strictly limited to a traffic signal carrying a message such as "Do not enter" or "Stop," but may be used for an advertising sign or for a traffic signal carrying some other message.

It will be understood that numerous modifications may be made without departing from the spirit of the invention in regard to details of fastening and the like, and I therefore do not intend to limit myself in any manner other than as set forth in the claims which follow.

Having now fully described my invention, what I claim as new and desire to secure by Letters Patent is:

1. In a traffic signal, a housing, a light source in said housing, a message panel in front of said light source, and a bank of closely spaced thin parallel slats arranged one above the other in front of said message panel, said slats being dis-

posed at an angle between about 2° and about 5° to the horizontal.

2. The structure of claim 1 in which said message panel comprises a translucent message on a black, opaque ground.

3. The structure of claim 1 in which said casing includes a hood extending forwardly of said message panel and said slats, the interior of said hood, and said slats, being flat black in color.

4. The structure of claim 1 in which a white 10 mesh screen is disposed between said message panel and said bank of slats.

5. The structure of claim 1 in which said slats are fixed to a frame, the individual slats being perpendicular to the plane of the frame, and the 15 frame being disposed at an angle of from about 85° to about 88° to the horizontal.

6. The structure of claim 5 in which said frame

is pivotally mounted adjacent its top and in which releasable means are provided adjacent the bottom thereof to permit said frame to be swung out for access to said message panel.
